LAPPING DEVICE

Raymond R. Searles, New Britain, Conn., assignor to The Fafnir Bearing Company, New Britain, Conn., a corporation of Connecticut

Application August 6, 1937, Serial No. 157,648

2 Claims. (Cl. 51—105)

My invention relates to what I term a lapping device, but which may be adapted for grinding, honing, polishing, etc., all of which operations I wish to include within the term "lapping."

5 It is the principal object of my invention to provide an improved lapping device, particularly though not exclusively adapted for lapping the raceway grooves for ball bearings.

It is a further object to provide an improved 10 lapping device which may be very readily actuated.

A further object is to provide an improved 15 lapping device so arranged and operated that it may be very readily and quickly brought into and out of lapping position.

Another object is to provide an improved lapping device in which the lapping pressure may be quite readily predetermined and maintained.

Other objects and various features of invention will be hereinafter pointed out or will become apparent to those skilled in the art.

In the drawing which shows, for illustrative purposes only, preferred forms of the invention—

Fig. 1 is a side view in partial section of a 20 lapping device, illustrating features of the invention;

Fig. 2 is a fragmentary view, similar to Fig. 1, and illustrating a slightly modified form of the invention.

30 In the particular embodiment of the invention herein illustrated for lapping the raceway grooves of ball bearings, I employ what may be termed a lapping head 5 carried by and bodily rotatable with a spindle 6 rotatably mounted in ball bearings such as 7 carried by a frame 8. The lapping head 5 carries movable lapping tools 9—9, which in the form illustrated are pivotally mounted as at 10 to the lapping head so that the laps proper 11—11 may be moved into and out of engagement 35 with the work which, as illustrated, is an outer ring 12 of a ball bearing. The ring 12 is carried in a suitable pocket chuck 13 on a rotatable spindle 14. The lapping tools are movable preferably by fluid pressure actuated means in at 40 least one direction. As illustrated, the spindle 6 is hollow and carries an actuator or draw rod 15. Adjustably mounted on the front end of the draw rod 15 is a toggle head 16 and toggle links 17—17 are pivotally connected to the toggle head 45 and the lapping tools 9—9 so that when the actuator 15 and toggle head 16 are moved toward the right the laps 11—11 will be urged into engagement with the work and, conversely, when the head 16 and actuator 15 are moved toward the 50 left, the laps 11—11 will be moved substantially

radially away from the work so as to permit the chuck to be withdrawn and a new work piece substituted.

The actuator 15 in the preferred form is operated by fluid pressure actuated means, which 5 may include a piston 18 carried by the rear end of the actuator rod 15 and mounted in a cylinder 19, as will be understood. Fluid pressure passages 20—21 communicate with the cylinder at opposite ends of the piston 18 and fluid pressure passage members or pipes 22—23 communicate respectively with the passages 20—21 and serve to conduct pressure fluid to and from the ends of the cylinder, as will be clear. The pipes or passage members 22—23 may be connected to an ordinary three-way valve, entirely familiar to those skilled in the art, whereby fluid may be directed at will to the cylinder at one side of the piston 18 and exhausted from the other side so as to actuate the actuator rod 15 and thus rock 10 the toggle for actuating the lapping tools 9—9.

In that form of the invention shown in Fig. 2, the parts may be substantially the same as those shown in Fig. 1. However, the lapping tools 9—9' are provided with bulges or other means to 25 provide greater weight, since in the form shown in Fig. 2 the tools 9—9' are adapted to be thrown outwardly centrifugally so as to bring the laps 11—11 into engagement with the work. The toggle head 16 may be the same as heretofore described and preferably the links 17—17' are connected to tools 9—9' by a pin and slot connection indicated generally at 24. In that 30 form shown in Fig. 2, the work head spindle 14 is mounted on one axis, the center line being 35 shown in dot-dash lines, while the spindle 6 is mounted upon another axis out of alignment with the axis of the work spindle 14. Therefore, the laps 11—11 being generally concentrically 40 and symmetrically arranged relatively to the axis of the spindle 6, the laps will engage the raceway groove of the ball bearing constituting the work piece at opposite sides of the groove when the lapping tools are arranged oppositely, all as will be clear from Fig. 2. During rotation of the 45 lapping head and the work head at different speeds, the laps will traverse the raceway groove in generally spiral fashion so as to lap the entire surface. With the work head and the lapping head mounted on the same axis, as may be considered the condition in Fig. 1, the laps 11—11 will simply track around within the raceway groove and may be considered as form laps, whereas the laps 11—11 of Fig. 2 need not be 50 form laps since the shape of the lap is not relied 55

upon for lapping the surface, owing to the fact that the laps traverse the entire surface of the groove.

In the form shown in Fig. 2, as stated the laps are designed to be thrown out into lapping engagement with the work by the centrifugal action of the tools themselves. The laps may be drawn in radially by fluid pressure actuated means, as heretofore described, and the pin and slot connection is provided to permit free centrifugal action of the laps during the lapping operation and yet permit the laps to be fully retracted by the toggle mechanism. The laps of Fig. 1 as indicated are designed to be moved both into and out of engagement by means of the toggle lever mechanism shown. By providing a yielding connection between the lapping tools 9—9' and the toggle head 16, the axes of the spindles 14 and 6 could be offset so as to cause the laps 11—11' to traverse the entire groove after the manner of Fig. 2.

By means of the toggle actuation of the lapping tools very slight force is required to move the lapping tools and the latter may be retracted to permit the insertion of a new work piece, all without stopping the rotation of the spindle 6. The fluid pressure actuated means which in the form shown in Fig. 1 serves to urge the laps into lapping engagement with the work is highly advantageous in that there is a substantially constant and uniform pressure urging the laps into engagement with the work and that pressure tends to follow up so as to cause a substantially constant pressure on the laps even though they may wear to some extent. By properly proportioning and adjusting the toggle mechanism as well as the fluid pressure in Fig. 1, the lapping pressure may be very accurately predetermined and maintained. By properly designing the lapping tools 9—9' of Fig. 2 and rotating the spindle at the proper speed, the lapping pressure may also be accurately predetermined.

A lapping device built in accordance with my invention is rapid in production in that the lap-

ping tools may be rotated constantly and the work head withdrawn and new work pieces substituted, all without stopping the rotation of the lapping tools and when the work head rotates at a sufficiently slow speed, without stopping its rotation. It may be said that, generally speaking, the lapping tools are rotated at a rapid rate while the work piece is rotated quite slowly.

It will be clear to those skilled in the art that the device may be arranged for lapping the race-way grooves of inner rings of ball bearings.

While the invention has been described in considerable detail and two forms illustrated, it is to be understood that the invention may be variously embodied for lapping various articles and surfaces and that changes and modifications may be made within the scope of the invention as defined in the appended claims.

I claim:

1. In a device of the character indicated, a support, a spindle rotatably mounted thereon, a cylinder fixedly mounted on one end of said spindle, a lapping head fixedly mounted on the other end of said spindle, lapping members carried by said head, actuating members for said lapping members, a piston in said cylinder, a piston rod passing axially through said spindle and connected to said piston and said actuating members, means for subjecting said piston to fluid pressure for actuating said lapping members, and means for rotating said spindle, cylinder and lapping head as a unit.

2. In a device of the character indicated, a support, a spindle rotatably mounted thereon, a lapping head carried by said spindle, lapping members carried by said head, toggle mechanism for actuating said lapping members in at least one direction, a toggle actuator connected to said toggle mechanism and passing axially through said spindle, and fluid pressure actuated means for moving said toggle actuator for the purpose described.

RAYMOND R. SEARLES.
